DESIGN FOR A BIRD CAGE

George Lorenze Miller, Decatur, Ill., assignor to Faries Manufacturing Company, Decatur, Ill.

Application December 17, 1936, Serial No. 66,595

Term of patent 3½ years

To all whom it may concern:

Be it known that I, George Lorenze Miller, a citizen of the United States and a resident of Decatur, in the county of Macon and State of Illinois, have invented a new, original, and ornamental Design for a Bird Cage, of which the following is a specification, reference being had to the accompanying drawing forming part thereof.

The figure is an elevational view of a bird cage, showing my new design.

I claim:

The ornamental design for a bird cage, substantially as shown.

GEORGE LORENZE MILLER.
